ROCK CRUSHER AND DISINTEGRATOR

Maude E. Meinhardt, Los Angeles, Calif., assignor
to Hallie M. Melvin, Los Angeles, Calif.

Application September 15, 1941, Serial No. 410,837

3 Claims. (Cl. 83—53)

This invention relates to a rock crusher and disintegrator, and though more particularly intended for this purpose may also be used to advantage to crush and grind various other hard substances.

It is an important object of the invention to improve upon the contour and mounting means for that portion of the crushing jaws which are subjected to the greatest pressure and strain.

Another object of the invention is to provide a more compact and simple arrangement of means for actuating the crushing or grinding jaws, whereby adequate leverage is afforded and at the same time sufficient strength of the operating means is provided to safeguard against breaking when the machine is subjected to severe strain.

Another object is to provide improved means for removably supporting the crushing jaws or protecting linings for them so that worn out parts may be easily removed and replaced, and yet will be securely held in their operative positions.

A more specific object of the invention is to provide an upstanding pulverizing jaw structure so constructed as to combine a hopper structure with a jaw structure in an improved manner.

Yet other objects relate to general simplification and more sturdy construction of the machine of the class to which the invention pertains.

The invention also includes the provision of a machine capable of performing a two-step crushing process, whereby materials fed to the machine to be pulverized are first reduced to a predetermined degree of fineness, the machine thereupon further crushing the material until it is reduced to a powder of the desired degree of fineness, or mesh.

Still other objects, advantages and features of invention may hereinafter appear.

Referring to the accompanying drawing, which illustrates what is at present deemed to be a preferred embodiment of the invention,

Fig. 1 is a view of the crusher as seen partly in side elevation and partly in vertical section, the sectioned portion of the view being on line 1—1 of Fig. 2. In this view limits of jaw movement are indicated by broken lines.

Fig. 2 is a view showing the crusher partly in plan and partly in transverse section, the sectioned portion of the view being on line 2—2 of Fig. 1.

Fig. 3 is a sectional detail taken on line 3—3 of Fig. 1.

Fig. 4 is a fragmental elevation of a foot portion of the casing.

Fig. 5 is a fragmental vertical section on a reduced scale, illustrating a modification.

Referring in detail to the drawing, a box or casing structure 10 is shown having an open top. The side walls 11 of this casing cooperate with a stationary jaw 12 and a movable jaw 13 to afford a downwardly directed feed passage or hopper structure into which is fed the material being disintegrated. Near its upper end said stationary, though adjustable, jaw 12 has a backward extension 15 having through it an aperture or horizontal bore 16 through which passes a bar or sturdy pin 17, the casing side walls 11 having upper corner portions which support the end portions of said bar. A spacer sleeve 18 surrounds the portion of the bar 17 which bridges the space between the casing walls 11.

The jaw 12 is adjustable by means of a pair of follower bolts 19 to vary its inclination and also to vary the distance of upper and lower 25 working faces with which it is provided, from the movable jaw 13. Said follower bolts extend through screw-threaded bores provided for them in lugs 20a located in corners formed at the juncture of casing foot members 20 with the casing side walls 11. The inner ends of said bolts abut against the sockets or seats 21 formed for them in the outer side of a horizontal follower bar 22 which, as seen in cross section, is shaped as a truncated wedge, the narrow side 35 of which is directed upwardly.

That side of the foot portion of the movable jaw 13 which is opposite to the follower bar 22 engages an antifriction roller 23 carried by bearings 24 one of which is located at each side of 40 the roller which extends from side to side of the machine.

The movable jaw 13 is supported in a pendant manner by means of a rocking shaft 25 which passes through its enlarged upper end portion 45 26, said shaft 25 having beyond the sides of the jaw projecting end portions each of which is supported by the short arm 27 of a lever fulcrummed on a cross bar 28, said lever having a longer, downwardly extending operating arm 29. At each side of the crusher the lever arm 29 has its lower end pivotally connected to a link 31 driven by a crank pin 32 carried eccentrically by a shaft 33, to which is fixed the combined flywheel and pulley 34, driven by a belt 35. It will be observed from Fig. 3 that a

simplified crank structure results from the fact that the shaft 33 is made of a sufficiently large diameter to secure the desired eccentricity for each crank pin 32 when the latter is formed as an integral extension confined within the periphery of that end of the shaft which carries such crank pin. Further advantages of this crank structure are greater ease of assembling and disassembling. The side walls 11 of the machine are provided with substantial bearings 36 for said shaft 33. The combined fly wheel and pulley 34 has annular end bosses or hub portions 34h which have a working contact with the side walls of the casing.

The grinding face 40 at the lower portion of the movable jaw is convex and is formed upon a shoe 41 which runs from one side to the other of said jaw. Said shoe is beveled along its upper and lower edges in such a manner as to make its back face narrower than its pulverizing face, and is fitted into the lower end portion of a long, vertically extending recess in the jaw 13, the lower end of said recess being bounded by the downwardly inclined shoulder 42, while the upper end of said recess is undercut to form the shoulder 43. In said elongated recess is first inserted the jaw facing member 44, so that when the shoe 41 is put into place as shown it serves to lock said facing member in place. The shoe 41 is attached by means of a bolt 45 near each end, these bolts having angular heads in correspondingly shaped recesses in the shoe so that they cannot turn. Onto opposite ends of said bolts are screwed nuts 47 located in recesses so as not to be engaged by the antifriction roller 23. In addition to the securing means for the facing plate 44 afforded by the attached shoe 41 a pair of securing bolts 49 are provided for the lower portion of the facing plate 44, these bolts having flared heads located in sockets provided for them in the plate and having nuts 60 screwing onto their opposite ends.

The stationary jaw 12 has its foot portion provided with a pulverizing face 65 which is formed upon a shoe 66 of greater width than the shoe 41 already described. Said shoe has a pair of securing bolts 67 in its lower end portion, these bolts being like the bolts 59 already described, their nuts 68 being located in recesses provided for them in the back of the jaw 12. The upper edge portion of the shoe 66 has securing bolts 70 which are like the bolts 67 except that they are shorter, and are likewise provided with nuts 71.

Above the shoe 66 the jaw 12 is provided with a face plate 73 which is beveled at its lower end at 74 where it meets a reversely beveled surface along the upper edge of the shoe 66 which serves to lock the lower portion of said plate in place. The upper portion of said plate 73 is beveled and underlies a reversely beveled, undercut shoulder 77 in the upper portion of the jaw thus completing the means for holding said plate in its attached position. Said face plate 73 is provided with a series of feed teeth 73a which cooperate with a series of feed teeth 44a provided in the face plate 44 of the jaw 13. Both these series of teeth have their largest teeth in the mid-length of the series, the size of the teeth diminishing upwardly and downwardly in each case. The shoe 66 may be regarded as a downward extension of the lining 73.

The facing plate 73, in conjunction with the 75

shoe 74 therebelow provides a feeding recess 78 which is bounded above by an angular shoulder 79, and this recess cooperates with an opposed recess 44r in the lower part of the facing plate 44 of the movable jaw 13. Superjacent to these recesses the facing plates 44 and 73 are respectively provided with short smooth face portions 44f and 74f, these smooth face portions defining an isthmus through which the material is fed from the upper hopper cavity 10h into the lower hopper cavity 11h, the latter hopper cavity being formed as a result of the oppositely disposed recesses just mentioned.

The curvature of that part of the movable jaw 15 which is engaged by the roller 23 is approximately the same in degree as that of the adjacent, parallel grinding face of the same jaw, and this insures that, during operation, a uniform clearance is maintained between the opposed grinding faces adjacent to said roller. As a result, no ore can be discharged from between the two jaws until it has been ground to a predetermined degree of fineness.

It is to be understood that, although only a 25 single pair of jaws have been shown and described, yet a plurality of pairs of such jaws may be embodied in a single machine without exceeding the scope of the claimed invention.

The general compound movement of the movable jaw 13 is indicated by double headed arrows.

In order further to stabilize the attached linings 44 and 73 they are respectively furnished with rectangular backward projections 44x and 35 73x which are seated in correspondingly shaped jaw recesses provided for them.

The toothed portions of the lining members 44 and 73 crush the material fed to the machine and the grinding or pulverizing is performed lower down between the shoes 41 and 66.

In order to protect the inner faces of the side walls 11 of the casing from injurious wear, a wear plate 80 is fitted into a suitable recess provided for it in the inner face of each side 45 wall of the casing.

The left hand portion of the casing as viewed in Fig. 1 is provided with clamping bars 85 surrounded by spacing sleeves 86 and having nuts 88 on their ends, while in the opposite end portion of the casing there are also clamping bars 85 surrounded by sleeves 86 and furnished with nuts 88.

In Fig. 5 is shown a modified form of lining and shoe structure for the jaws, the stationary 55 jaw 12 carrying a shoe 90 having a face 91 slightly concave throughout its lower portion and the lining member 92 having a straight flat outer face that is in alinement with said face 91. The movable jaw 13 has a shoe 95 similar to the shoe 40 of Fig. 1, but its lining member 96 has no hopper recess, but has a slightly convex toothed portion 97. Otherwise this view has reference numerals like those of Fig. 1.

In both embodiments of the invention the casing has a delivery opening 98 between foot portions 20 and 99.

I claim:

1. In a crusher, a casing, a stationary jaw mounted thereon having a lower end portion furnished with a grinding face, a pendant movable jaw carrying in its lower portion a grinding face which is convex in its vertical extent, an antifriction roller engaging the side of said pendant jaw opposite to its said face to maintain it in a close working relation to the grind-

ing face of said stationary jaw, said casing having opposite side walls between and by which said roller is horizontally supported, a horizontal fulcrum shaft supported by the casing, a lever carried by each end portion of said shaft, said levers each having an upper and a lower limb in relation to said shaft, the upper ends of said levers being inclined toward the top of said stationary jaw, a rocker shaft extending through the upper parts of said inclined limbs and through the upper part of said movable jaw thereby pendants supporting said jaw between and below said inclined limbs, and means operatively connected with the lower ends of said levers to oscillate them in unison.

2. The subject matter of claim 1 and, said stationary jaw having a transversely extending recess superjacent to its grinding face and a feed shoulder along the upper side of said recess, said shoulder maintaining a closely adjacent re- 20

lation to the grinding face of the moving jaw during the operation of the machine.

3. In a crusher, a casing, a crushing and grinding jaw mounted thereon, a driving shaft mounted on said casing, said shaft having a crank pin projecting eccentrically from and formed as an integral extension of an end portion thereof, said crank pin being located within the circumference of the end portion of the shaft from which it projects, a link having one end portion operatively related to said crank pin, means operatively related to the opposite end portion of said link to operate said jaw, and means to rotate said shaft, said casing having side walls, and said means for rotating said shaft including a combined fly wheel and pulley fixed thereto between said casing walls, said wheel having hubs in a working fit relative to the inner faces of said walls.

MAUDE E. MEINHARDT.
